W. Bushnell.

Metal Drill.

No. 8,554.

Patented Dec. 2, 1851.

UNITED STATES PATENT OFFICE.

WILLIAM BUSHNELL, OF NEW YORK, N. Y.

HAND-DRILL.

Specification of Letters Patent No. 8,554, dated December 2, 1851.

To all whom it may concern:

Be it known that I, WILLIAM BUSHNELL, of the city, county, and State of New York, have invented certain new and useful Improvements in Drilling-Machines; and I do hereby declare that the following is a full, clear, and exact description of the same, reference being had to the accompanying drawings, forming part of this specification, in which—

Figure 1 is an isometrical view of one of my improved machines; Fig. 2: is a vertical section of the same. Fig. 3: is a plan or top view of the opening and closing nut or screw nippers. Fig. 4, is a sectional view showing the manner of adjusting the movable head.

Similar letters of reference indicate corresponding parts in each of the several figures.

My invention consists in the employment for the purpose of giving the necessary pressure to the drill, of a helical spring coiled around the drill shaft and suitably confined and having its pressure controlled by means of a male screw on the said shaft and a nut suitably placed and formed in two parts or in the two jaws of a pair of nippers, which can either be closed upon the male screw or released from it at the pleasure of the operator, the nut when closed upon the screw enables the spring to be set up or enables the drill to be withdrawn from its work by turning the shaft, but when released from the screw allows the drill to be operated upon by the spring.

To enable those skilled in the art to make and use my invention I will proceed to describe its construction and operation.

A is the foot plate of the machine which carries two parallel rods or standards B, B, perpendicular to it, forming the guide frame for carrying the adjustable head. The adjustable head consists of a hollow cylinder or socket, C, having two ears, a, and, b, on each side which are bored to fit the rods, B, B; in front of each of the upper ears, a, a, are a pair of small lugs, c, c, through which are inserted a pin, d, forming the fulcrum of a small lever, e; to the upper end of this small lever is jointed a catch tooth, h, which passes through the ear, a, and fits into either one of a series of notches, f f, in the rods B B; between the lower end 55 of the small lever and the ear is placed a small spring, g, which always tends to force

the catch tooth, h, into one of the notches f f, the catch tooth being in a notch prevents the ascent of the head but owing to the shape of its point and the corresponding shape of the notches allows its descent.

D is the drill shaft having a socket at its lower end to receive the drill E, it is parallel from the upper end to, i, where there is a shoulder and has a screw, j, part of the way along it, its upper part fits in the upper end of the socket C and its lower part in the lower end of the socket which is made larger between the ends to receive the helical spring F which coils around the shaft and rests upon the shoulder, i, its upper end bearing against a shoulder, h, in the upper part of the socket, I, is a crank for turning the shaft.

Attached to the upper end of the socket and forming part of the adjustable head, is a small frame, G, in which is a guide, C, for the upper part of the drill shaft, at the back of this frame is an arm, m, the top of which stands flush with the top of the socket, C.

H H represent the nippers which lay flat on the top of the socket C and arm, m, being secured to the arm, m, by a screwed pin, n, which passes through their ends and serves for them to work upon. At opposite points in each jaw is cut the female screw which forms an opening and closing nut for the screw j. To one handle of the nippers is attached a spring catch, p, which catches into a recess in the opposite handle, and holds the nippers together when they are closed. In Fig. 3, the nippers are shown closed upon the screw, but in Fig. 1 they are represented open and the drill shaft free.

The foot plate A may either be permanently secured by bolting to any suitable foundation or may be secured in any suitable position by a cramp or other fastening to the object to be drilled or to a bench or table.

The operation of the machine is as follows. The work being placed under the drill or the machine being attached or applied to its work it will be necessary to adjust the spring to give what may be considered by the operator a suitable pressure to the drill. This is done by closing the nippers, H, H, upon the screw, j, and turning the shaft until the spring is sufficiently contracted, the adjustable head is then brought to a suitable position on the guide rods or standards, B, B, to bring the point of the drill to the

- work, the nippers are then opened and the shaft left free, rotary motion is then given to the shaft in the proper direction, in which the drill cuts and the expansion or opening 5 of the spring gives the necessary pressure to the drill, when the hole made by the drill is of the required depth, the nippers are closed upon the screw, *j*, and the shaft turned in the proper direction to raise or withdraw it.
- 10 In some instances where the hole to be drilled might be of great depth the opening of the spring might reduce its pressure so much that it might require to be contracted which can be done by merely closing the nippers 15 upon the screw and turning the shaft in the proper direction to raise the drill, after which the adjustable head can be lowered to bring the drill to its work. For drilling a number of holes of a moderate depth, where 20 the machine can be used stationary, the adjustable head will not require any adjustment after being set to the proper position

for the first hole. When it is necessary to raise the head, the catches, *h*, *h*, must be withdrawn by pressing on the lower ends 25 of the levers, *e*, *e*, when the head is left free to slide upward.

What I claim as my invention and desire to secure by Letters Patent is—

The combination of the helical spring *F*, 30 with the screw, *j*, upon the drill shaft and the opening and closing nut or screw nippers, *H*, *H*, the whole being applied in the manner substantially as described and operating for the purpose of controlling all 35 the required movements of the drill in the line of the axis of its revolution, in giving it the pressure upon its work; controlling the said pressure and withdrawing it from its work as herein fully set forth.

WILLIAM BUSHNELL.
